Chicago, Ill., a corporation of Illinois

Application August 14, 1933, Serial No. 685,048

24 Claims. (Cl. 175—298)

This invention relates to electric switching stations of the type wherein the circuit breakers are mounted on an elevator for raising and lowering the breakers into and out of their operative positions, and particularly to installations wherein the breaker terminals or bushings are provided with switching means which serve as disconnect switches for the breakers, the disconnect function being attained by raising or lowering of the entire circuit breaker mechanism. Such installations include a stationary supporting structure containing an elevating housing mechanism for receiving the circuit breaker and elevating or lowering the same.

It is one of the objects of the present invention to provide a novel support for the breaker and the hoisting mechanism. When the circuit breaker is in its operative position it is desirable that the breaker be held firmly in place, in order that it may better be able to withstand the reactions incident to opening of the circuit under adverse conditions. In order to prevent upward movement of the circuit breaker head during circuit interruptions under extreme short circuit conditions, it has been customary to provide means for clamping the breaker to the hoisting mechanism. This is objectionable. In the first place, it means that the elevating or hoisting mechanism takes all of the reaction incident to a violent switch-opening operation. In the second place, it complicates the operation of placing the breaker on the elevating mechanism and the operation of removing the breaker from the elevating mechanism. We propose to cure these defects. We eliminate all clamping means for securing the circuit breaker to the elevating mechanism. In our improved arrangement the circuit breaker rests, by its own weight, on the elevating mechanism, which mechanism is free of any arrangement for holding the breaker head against upward movement with respect thereto under severe circuit interrupting conditions. When the circuit breaker is elevated to its operative position it abuts against a stop which is a part of the stationary structure, such stop serving to hold the breaker against upward movement under the forces induced during violent circuit interruption. This frees the hoisting mechanism of the stresses that would be induced therein if the hoisting mechanism were relied upon to hold the breaker down during violent circuit interruption. The elevator mechanism comprises a pair of arms between which the circuit breaker, mounted on a truck, may be moved. The arms are then movable vertically upward to engage and elevate the breaker. The breaker is held on the elevator

mechanism solely by its own weight. This facilitates the removal of the breaker from the elevator mechanism, because it is only necessary to move a truck under the breaker and then, by lowering the elevator mechanism, bring the breaker onto the truck and free the breaker from the elevator mechanism.

It is a further object of the present invention to provide a three-point support between the elevator mechanism and the breaker head. This provides a simple manner of mounting the breaker and assures the uniform distribution of stress due to the weight of the breaker.

It is a further object of the present invention to provide an improved interlock between the circuit breaker, the elevating mechanism, and the stationary structure, so as to prevent raising or lowering of the circuit breaker except when the breaker is in its switch-open position. We provide a structure, carried by the circuit breaker itself, for positively locking the hoisting mechanism to the frame whenever the switch is in its closed position. By this arrangement it is impossible to commence the circuit breaker lowering operation until the breaker has been tripped.

We are aware that it is old to provide for automatically tripping a circuit breaker upon the commencement of the lowering of the hoisting mechanism. Such arrangements of the past include a lever connected to the circuit breaker tripping mechanism and carrying a roller, which rests in a notch in the stationary supporting structure, so that upon the downward movement of the elevator mechanism the roller is pushed out of its notch and actuates the tripping mechanism for tripping the circuit breaker. Such mechanism is open to serious objection. If the circuit breaker happens to be carrying a heavy load at the time of lowering, the violent reaction resulting from the forces produced incident to the tripping operation must be carried by the elevator mechanism at a time when it is not locked to the frame but is moving downwardly. This imposes an undue strain upon the elevator mechanism. By our improved arrangement the lock between the elevating mechanism and the stationary structure cannot be released until the circuit breaker has been tripped. Thus, there is a definite assurance that, at the time of tripping of the circuit breaker, the elevating mechanism is locked in position.

It is a further object of the present invention to provide an arrangement which will prevent closing of the circuit breaker before the elevator mechanism has been locked against lowering, and to prevent unlocking of the elevator mechanism

while the circuit breaker is in its closed position. By this arrangement there is a definite assurance that the elevator mechanism is locked in position whenever the circuit breaker is closed, so that the elevator mechanism cannot be subjected to violent reaction incident to circuit breaker operation under adverse conditions when the elevator mechanism is unlocked.

It is a further object of the present invention to provide an arrangement wherein the interlock between the elevating mechanism and the stationary supporting structure will not be subjected to excessive strain in the event that an attempt is made to lower the mechanism when it is locked to the stationary structure. We accomplish this by providing an arrangement which will cause binding between the elevating mechanism and the stationary supporting structure if an attempt is made to lower one end of the elevating mechanism when the other end is held by the interlock against lowering.

The attainment of the above and further objects of the present invention will be apparent from the following specification, taken in conjunction with the accompanying drawings forming a part thereof.

In the drawings:

Figure 1 is a side view of a switching unit embodying the principles of our invention, said view being taken along the line 1—1 of Figure 3;

Figure 2 is a top view taken along the line 2—2 of Figure 1;

Figure 3 is a view taken along the line 3—3 of Figure 1 and illustrating the front of the mechanism when the front cover plate is removed;

Figure 4 is a right side view of the mechanism, with the cover removed, and illustrating the circuit breaker in its elevated position, said view being taken along the line 4—4 of Figure 3;

Figure 5 is a sectional view of the interlock between the circuit breaker operating shaft and the transfer switch operating shaft, said view being taken on the line 5—5 of Figure 1;

Figure 6 is a perspective view of the elevator mechanism;

Figure 7 is a diagrammatic view illustrating the operation of the shutter mechanism;

Figure 8 is a view taken along the line 8—8 of Figure 7;

Figure 9 is a fragmentary sectional view of the transfer plug used on the circuit breaker;

Figure 10 is a fragmentary view illustrating the rear of the circuit breaker;

Figure 11 is a fragmentary perspective view illustrating the interlock between the circuit breaker and its support; and

Figure 12 is a fragmentary sectional view taken along the line 12—12 of Figure 1.

Each unit is metal enclosed, with self-contained factory assembled switch gear and busses wired and ready for installation. Each unit comprises a stationary element or cubicle and a removable element comprising an oil circuit breaker of the vertical lifting and lowering type. The stationary element or cubicle is indicated at 1, and comprises a rigidly braced welded structural steel supporting frame with heavy sheet metal enclosures. The cubicle is divided into an upper compartment 2 containing the busses and the transfer switching equipment, and a lower compartment 3 containing the elevator mechanism for the oil circuit breaker, the switch control apparatus, the shutter control apparatus, the interlocks, and, optionally, the metering transformers. The lower compartment is provided with a

removable rear panel 5 for permitting access to the rear of the cubicle. It is also provided with a front recessed door 6 formed of stretcher level steel hung on concealed hinges so that the door face is flush with the front of the unit when closed. The sides of the lower compartment are enclosed by sheet metal panels 7—8. The enclosure for the upper compartment is separate from the enclosure for the lower compartment, and comprises side panels 9 and 10 which are provided with openings for extending connections to the busses, front and rear panels 11 and 12, and top panels comprising three separate sections, 13, 14 and 15. All the panels are secured to and removable from the structural steel frame. 15

A three-phase main bus 16 and a three-phase transfer or reserve bus 17 are mounted in the upper compartment and extend the full width thereof, being separated by a barrier 18 of "Bakelite" or other suitable insulation. Each set of 20 busses is rigidly supported by two pairs of bars 19—19 of suitable insulation, such as "Bakelite", which embrace the bus bars and securely clamp them in place, the bars 19—19 being, in turn, rigidly secured together by metal cross members 25 20—20 and suitable hangers. Laminated copper taps 22 are welded or otherwise secured to the respective bus conductors 16, each of the taps terminating in a cylindrical plug 21 which constitutes the male terminal of a primary plug disconnect switch 23, as will be more fully described as this description proceeds. Each bus conductor, with its associated tap, is enclosed in wrapped insulation comprising a laminated paper insulation wrapped under tension, each layer being 30 coated with phenolic varnish, solidly pressed, and cured in heated molds. This insulating method eliminates voids, looseness, warps and cracks. A three-phase bus unit comprises the bus, its support, bus taps and stationary ends of plug 21 with 40 their insulating bushings 23A. This is assembled before installation in the cubicle and may be easily removed as a unit. The ends 24 of the busses are silver plated and, with their bolted connections between splice plates that extend the 45 connections to or from the busses, insure permanently high conductivity.

Each of the plug disconnectors 23 for the main bus includes a tube of insulation 23A of suitable insulation such as the material known as "Bakelite", which tube is divided into upper and lower parts by an internal web 23B having an opening through which the male plug 21 extends. The plug is secured to the web by a suitable nut. The three tubes of insulation 23A of the main bus 50 extend through openings in an escutcheon plate 23C and are secured thereto, the lower portion of each tube of insulation extending through the escutcheon plate. This completes the main bus unit for mounting within the upper compartment of the cubicle. In assembling the bus within the cubicle the escutcheon plate is secured to the base of the upper compartment 2. The upper part of the tube of insulation 23A is filled with insulating compound after assembling 55 of the bus. The auxiliary or reserve bus disconnector 23' and the line disconnector 34 are of a construction similar to that of the main bus disconnector 23. 60

The reserve or transfer bus 17 is of a construction substantially identical to that of the main bus 16. The taps 25 that are connected to the reserve bus correspond to the taps 22 of the main bus, and are each provided with an additional tap 26, covered with insulation as are the taps 70 75

22, and extending the electrical connection from the reserve bus, through insulating bushings 27 supported by a plate 28, to a stationary terminal 29 of a transfer switch 30. There are three such switches, one for each phase. The blades of the disconnect switches are mounted upon hinge terminals 31 supported by insulators 32. The hinge terminal 31 of each transfer switch 30 is connected, by way of an insulated tap 33, to a male plug similar to the plug 21, and comprising a part of the plug disconnectors 34. Insulating barriers 35 and 36 of the material known as "Bakelite", or the like, separate the taps 33 from the taps 25 and 26. The hinge terminals 31 of the transfer switches 30 are connected to an incoming or outgoing line conductor by way of insulated taps 40 that extend through current transformers 41, to outgoing potheads 42. The transformers 41 are for metering purposes or the like.

The three switch blades are connected by insulating links 45 and cranks 46 to a shaft 47. Rotation of the shaft operates the three switches in unison. The shaft is rotated by a crank 48, a reciprocating rod 49, a crank 50, and a rotatable transfer switch operating shaft 51. The transfer switch operating shaft extends from the rear of the cubicle, through an interlock 52, to the front of the cubicle. The interlock 52 locks the shaft 51 against rotation in either direction except when the circuit breaker is in its elevated and closed position, as will be more fully described as this description proceeds.

The interlock 52 comprises an interlock sector 60 keyed to the shaft 51 and cooperating with an interlock latch lever 61 which is pivoted about a stationary pivot 62 and includes a projection 64 that extends in the path of movement of the interlock sector 60, as may be seen from Figures 1 and 5. An arm 65 is formed integrally with the interlock latch lever 61 and is engaged by a spring 66 for biasing the latch lever to its locking position. The interlock sector 60 is shown in the position it occupies when the transfer switch is closed. To open the transfer switch it is necessary to rotate the shaft 51 in a clockwise direction as seen in Figure 5. The interlock sector 60, however, abuts against the projection 64 of the interlock latch lever 61 and locks the shaft 51 against clockwise rotation. In order to free the interlock sector it is necessary to rotate the interlock latch lever 61 clockwise, as seen in Figure 1. This is accomplished by a link 67 which engages the arm 65 and, upon upward movement of the link, moves the arm 65 and the interlock latch lever clockwise until the projection 64 clears the interlock sector 60. This movement is against the action of the spring 66. Upward movement of the link 67 is obtained by means of a cam 68 which is mounted on the operating shaft of the oil circuit breaker and is brought into the position shown in Figure 1 when the oil circuit breaker is fully elevated. The cam 68 is shown in the position which it occupies when the circuit breaker is open. In this position it has not raised the latch 67. To release the interlock latch lever 61 it is necessary to operate the circuit breaker, thus rotating the cam 68 counterclockwise. This forces the link 67 upward, whereby the projection 64 clears the interlock sector to permit movement of the sector and rotation of the transfer switch operating shaft 51. The shaft 51 may now be rotated to open the transfer switch 30. If this is done, the sector 60 is brought into a position

where its lower edge is immediately above the upper edge of the projection 64 of the interlock latch lever. If the circuit breaker is then operated to its open position the cam 68 permits the spring to return the link 67 and arm 65 to the position shown in Figure 1, and thus return the interlock latch lever to the position shown in Figure 1. The interlock sector 60 is now immediately above the projection 64, whereby the projection 64 locks the shaft 51 against counterclockwise rotation, that is, against rotation in the switch closing direction. By this arrangement the transfer switch 30 can be operated to its open or to its closed position only when the circuit breaker is in position and is closed.

An explanation will now be given of the circuit breaker hoisting or elevating mechanism, and the supporting and operating means therefor.

The elevator supporting and operating mechanism comprises a worm gear of the jackscrew type, including a worm 75 supported against longitudinal movement and carrying a nut 76 which is held against turning with the worm 75, whereby the nut rides up and down on the worm as the worm is rotated. The lower end of the worm 75 is supported in a ball thrust bearing 77 which is, in turn, supported by a structural metal member 78 that extends upwardly from the bottom of the cubicle midway between the right and left sides thereof, and is suitably braced adjacent its top and bottom by cross members 79-80. At its upper end the worm shaft 75 extends into a gear box 82 which is bolted or otherwise suitably secured to a cross channel 83. The gear box includes an operating shaft 84 extending at right angles to the worm shaft 75, and coupled thereto by bevel gears within the box. A sprocket wheel 85 is mounted on the shaft 84 for rotating with the same, the sprocket wheel being driven by a chain 86 which, in turn, is driven by a smaller sprocket wheel 87 keyed to a hoisting mechanism operating shaft 88 that extends to the front of the cubicle. The forward end of the shaft 88 is squared for receiving an operating handle or an electric drill motor.

The circuit breaker holding and elevating mechanism is shown in Figure 6. It comprises a pair of angle iron members 90-90 welded or otherwise secured to a lower plate 91 and an upper angle iron member 92. Side arms 93-93 are welded to and extend forward of the respective angle iron members 90-90 and are braced at their outer ends by plates 94-94 that are welded to the side arms and to the angle iron members, respectively. Each of the side arms 93 has a trunnion receiving groove 95 and an interlock bar receiving slot 96. A locking lug 97 is welded or otherwise secured to one of the arms 93 for receiving a padlock to lock the elevator mechanism in its raised or lowered positions. The upper angle member 92 is provided at its center with an upstanding lug 98 having a curved upper surface constituting one point of support for a movable circuit breaker, as will be more fully set forth as this description proceeds. A slot 99 at the rear of the angle member 92 permits the angle member to embrace the worm shaft 75. The two side arms 93-93 are provided with outwardly extending lug projections 100-100 bolted or otherwise secured thereto. Flanged rollers 101 are secured to the outer sides of the bracing plates 94 and in alignment with the respective lug projections 100. A bar 102 is welded or otherwise secured to one of the

arms 93. This bar constitutes a support for a shutter-clutch operating cam, as will be more fully set forth as this description proceeds.

The elevator mechanism is assembled in the 5 cubicle so that the horizontal flange of the angle member 92 rests upon the nut 76, with the worm shaft 75 extending upwardly through the slot 99 in the angle member 92. At this time the flanged rollers 101 on the two bracing plates 94 bear 10 against upright guides 105—105 which are a part of the stationary cubicle structure. After the elevator unit has been placed in the cubicle, a second pair of flanged rollers 106, similar to the rollers 101, are secured to the outer sides of the side arms 15 93, said rollers 101 engaging the upright guides 105. Likewise, lug projections 107 are secured to the outer sides of the bracing plates 94, said lug 20 projections also engaging the upright guide 105. Also, a shutter operating cam or runway assembly 110 is bolted or otherwise rigidly secured to the bar 102 of the elevator mechanism so as to move up and down with the elevator mechanism.

The shutter operating cam 110 comprises a flat plate having a guideway 111 secured thereto and 25 extending almost, but not quite, to the top of the plate, and a short guideway 112 secured at the opposite edge and adjacent the top of the plate.

An explanation will now be given of the shutter mechanism and the means for controlling and 30 operating the same. For this purpose reference may be had more particularly to Figures 1, 7 and 8. The shutters are of identical construction and are indicated at 120, 121 and 122. Each of the 35 shutters comprises a rectangular plate 125 mounted on pivoted brackets 126 that pivot about stationary pivots 127. The shutters are adapted to be swung from a position covering the openings at the lower side of the plug disconnectors 23—23'—34, to a position free of the openings. 40 In Figure 1 the shutter 121 is shown in its closed position, that is, in a position covering the lower opening of the plug disconnector 23'. The shutters 120 and 122 are shown in their open positions, that is, in the positions uncovering the openings 45 of the plug disconnectors 23 and 34, respectively. An operating shaft 130 controls the operation of the shutters. This shaft is connected to the shutter 122 by means of a link 131 and a crank arm 132, so that rotation of the shaft 130 will always 50 actuate the shutter 122. The shutters 120 and 121 are selectively operated from the shaft 130 through a clutch mechanism 133. For this purpose the clutch mechanism has two cranks 135 and 136 extending therefrom and selectively connected to the operating shaft 130 by a clutch 55 operating lever 137 and a clutch collar 138, splined to and slideable on the shaft 130. The crank 135 is connected to the shutter 121 by means of a link 140, whereas the crank 136 is 60 connected to the shutter 120 by means of a link 141. Rotation of the operating shaft 130 will produce rotation of one or the other of the two cranks 135—136, depending upon which one of the cranks is clutched to the shaft 130, as determined 65 by the position of the clutch collar 139. This will produce an opening or closing of the corresponding shutter 120 or 121. The clutch is manually operated by means of an operating rod 143 that extends to the front of the cubicle and 70 is pivoted at 144 to an operating handle 145 which is itself pivoted at 146. A 180 degree clockwise rotation of the handle 145 shifts the clutch collar 138 from the position shown, where the main bus shutter 120 is operatively connected with the shaft 130, to its opposite position, where the re-

serve or transfer bus shutter 121 is operatively connected to that shaft, namely, from a position where the crank 136 is clutched to the shaft 130 to a position where the crank 135 is clutched to the shaft 130. It is to be understood that operation of the handle 145 merely shifts the clutch, it does not produce operation of the shutters. The exposed edge 147 of the operating handle 145 may have a letter "M" marked thereon, indicating that in this position of the operating handle 10 the main bus shutter will be operated. Likewise, the opposite end 148 of the operating handle may have the letter "R" marked thereon, indicating that in this position of the operating handle the reserve bus shutter is connected for operation. 15

The actual operation of the shutters is brought about by rotation of the shaft 130. This is accomplished through a crank 150 that is keyed to the shaft 130 and is pivotally connected to a link 151 (Figure 1) that is connected, at its opposite 20 end, to one arm 152 of a two-armed lever. This lever is pivoted about a stationary pivot 153 and has a second arm 154 which carries, at its outer end, a roller that rides against the guideway 111 of the shutter operating cam 110. The elevator 25 mechanism, and with it the shutter operating cam 110, is shown in its uppermost position. As the elevator is lowered, the roller at the end of the arm 154 rides against the guideway 111 until the elevator approaches its lowermost position. 30 At that time the roller clears the upper beveled edge of the guideway 111 and is forced to the right, that is, counterclockwise, by the lower beveled edge of the guideway 112. Counterclockwise rotation of the two-armed lever causes a corresponding rotation of the shutter operating shaft 130 through the link 151 and the crank 150. This causes operation of the shutter 122 and, the particular one of the shutters 120—121 that is 35 clutched to the shaft 130, in this instance the 40 shutter 120. This brings all the shutters to their closed position, that is, to a position the same as that of the shutter 121. If the elevator is subsequently raised, the upper beveled edge of the guideway 111 rotates the crank arm 154 clockwise, 45 thus producing a corresponding rotation of the shutter operating shaft 130. This causes an opening of the shutter 122 and of the connected one of the two shutters 120 or 121, in this instance 50 120. The opening of the shutters is accomplished at the initiation of the upward movement of the elevator. The closing of the shutters is accomplished at substantially the completion of the downward movement of the elevator. 55

The shutter mechanism has two distinct functions. First, since the shutters are always closed when the elevator mechanism is in its lowered position, they prevent accidental contact with the plug disconnectors that are connected to the busses or to the incoming or outgoing line. 60 Second, upon raising of the elevator mechanism, they uncover only the selected one of the two bus disconnectors and thus prevent accidental contact with the other bus. The operating handle 145 may be set in the position indicated in 65 Figure 1, and padlocked against operation. This permits the uncovering of the shutter that controls connections to the main bus, but it definitely precludes the establishment of connections to the reserve or transfer bus 17. Likewise, the 70 operating handle may be locked in its opposite position to permit access to the transfer bus 17 while precluding access to the main bus 16.

A circuit breaker 160 is provided for establishing connections between the conductor 33 (Fig- 75

5 tire 1) and the main bus or the transfer bus. The circuit breaker is here shown as a three-phase breaker and includes three socket terminals 161, one for each pole, for establishing connections with the corresponding phase conductors 33. It also includes three terminal studs 173 which, by means of an adapter or transfer plug 163, are adapted to cooperate with the plug disconnectors 23 or 23' of the main or of the transfer bus. The socket terminals are of a construction such as shown in the pending application of Alfred Alsaker and Fred H. Cole, Serial No. 681,158, filed July 19, 1933.

Briefly, the socket comprises a large number 15 of contact wires 164, swaged or otherwise suitably secured to a plug 165 that is threaded over a terminal stud 166 comprising one terminal of the circuit breaker. Coiled springs 167, in the form of rings, embrace the contact wire assembly 20 and urge the wires inwardly into firm engagement with a plug. A plurality of internal rings 168 limit the extent of inward collapse of the contact wires when the socket does not contain a plug. A sleeve 169 of suitable insulation 25 surrounds the contact socket for preventing accidental contact therewith. It is to be noted that the terminal studs 173 are appreciably below the terminal studs 166. When the adapter 163 is mounted in place it brings the overall height 30 of the corresponding terminal of the circuit breaker to that of the socket terminals 161.

The adapter comprises a transfer stud support 176 and a transfer plug 171. The transfer stud support comprises a copper bar 172, one end of 35 which is secured to the stud 173 that threads into a plug 174. The other end of the bar carries a stud that threads into a plug 175. The copper bar 172 is enclosed in a body of insulation 176 which is, preferably, molded around it and may 40 comprise any suitable insulation such as the material known as "Bakelite". The body of insulation includes cylindrical pockets surrounding each of the plugs 174—175. The transfer stud support includes a supporting leg comprising an insulating rod 178 and an insulating tubing 179 45 and a mounting base 180. The rod 178 is secured in place prior to baking of the insulation 176. The transfer plug is mounted in place with the male plug 174 connected to the threaded stem 50 173 of the breaker and with the base 180 resting upon and bolted to the circuit breaker head. A tube of insulation 181 surrounds the plug 174. A similar tube of insulation 182 surrounds the plug 175.

The transfer plug 171 comprises a body of insulation in one end of which is secured a pair of oppositely facing sockets 185 and 186, of a construction similar to the sockets 161. The opposite side of the transfer plug includes a cap 60 187 comprising an integral part of the main body of insulation and joined thereto by a bridge 188. A tube of insulation 189 surrounds the socket 185, being press fitted over a cylindrical portion 65 of the main body of insulation comprising the transfer plug. A spring clip 190, carried by the transfer stud support, extends through a centrally located opening in the bridge portion 188 of the transfer plug and serves to snap the transfer plug into its fully closed position when it is brought approximately to its fully closed position. In the position shown in Figure 9, the transfer plug covers the plug 174, the socket 185 70 being in a position to engage the plug 21 of the main bus conductors 22 (Figure 1). If desired,

the position of the transfer plug may be reversed so that the socket 186 engages the plug 174, and the cap 187 covers the plug 175. In this position of the transfer plug the socket 185 will engage the stud of the tap 25 from the reserve bus 17 75 (Figure 1).

The head of the circuit breaker 160 has mounted thereon an operating and tripping mechanism 195 which may be of any preferred construction. All of the operating mechanism 10 of the circuit breaker is carried by the head 200 thereof. A tank 201 is secured to the head 200 and encloses the interrupting mechanism, said tank carrying the bath of insulating arc quenching oil. A pair of trunnions 205—206 are 15 carried by blocks 207 and 208, that are welded or otherwise secured to the opposite sides of the head of the circuit breaker adjacent the front thereof. A rear support 209 is secured centrally of the rear of the head 200 and includes a 20 socket 210 which is adapted to seat on the lug 98 of the elevator mechanism, as shown in Figure 6.

Release bar pull rods 215 and 216 are carried by and slide in the blocks 207 and 208. These 25 pull rods are formed, at their forward ends, with eyes constituting handles. At their rear ends the release bar pull rods carry draw bar stops 217 and 218, which slide on draw bar support blocks 217a and 218a, respectively. These blocks are 30 welded to the circuit breaker head 200. The draw bar stops carry cam projections 219—220 that are engaged by stop cams 221 and 222, respectively, both of which are keyed to a shaft 223, constituting the main operating shaft of 35 the circuit breaker. The stop cams include a curved surface 224 of variable radius and a curved surface 225 of fixed radius. They also each include a flat surface 226.

Figure 11 shows the interlock mechanism of 40 the circuit breaker when the circuit breaker shaft 223 is in its switch closed position. The circuit breaker is held in the hoisting mechanism, the trunnions 205—206 resting in the trunnion grooves 95—95 in the side arms 93. At this time 45 the draw bar stops extend within the interlock bar receiving slots 96 in the hoisting mechanism. The drawbar stops 217—218 also rest on the upper surfaces of interlocking bars 230 that are 50 welded or otherwise secured to each of two upright channel-shaped structural members 231 comprising parts of the stationary cubicle. As long as the drawbar stop 217 or 218 rests on the interlock bars 230 and within the slots 96 of the arms 93, it is not possible to raise or lower the 55 hoisting mechanism. The drawbar stops 217— 218 cannot be retracted from the position shown in Figure 11 unless the switch operating shaft 223 is rotated to its open position, that is, counterclockwise as seen in Figure 11, so that the 60 stop cams 221—222 clear the cam projections 219—220 of the drawbar stops. Therefore it is not possible to lower the circuit breaker except when the breaker is in its open position.

As an additional precaution against any possibility of lowering the circuit breaker hoisting mechanism when the breaker is in its switch closed position, the release bar pull rod 215 is provided with a lug projection 240 which moves into engagement with and actuates a manual trip 70 241 (Figure 4) of the circuit breaker operating and tripping mechanism 195. Thus, even if the stop cam 221 were omitted so as to permit forward movement of the release bar pull rod 215 when the circuit breaker is in its closed position, 75

there would still be the definite assurance that the circuit breaker is tripped by the time the draw bar pull stop 217 clears the interlock receiving slot 96.

- 5 When the circuit breaker is elevated to its normal uppermost position the blocks 207-208 of the circuit breaker head bear against stops 246, which are welded to each of the channel upright members 231. This definitely limits the upward travel of the elevating mechanism and serves to hold the circuit breaker head firmly in place. The circuit breaker head is thus firmly held against all reactions incident to a violent circuit interrupting action. This rigid mounting 15 for the circuit breaker does not require clamping of the breaker to the elevating mechanism and thus permits the easy mounting or removal of the breaker from its supporting and elevating structure.
- 20 When the circuit breaker has been raised to its elevated position it is necessary to lock the elevating mechanism in position before the breaker can be operated to its closed position. This is done by pushing the drawbar stops 217-218 into the slots 96 in the arms 93 of the elevator mechanism and over the top surfaces of the interlock bars 230, to the positions shown in Figure 11. If an attempt is made to operate the circuit breaker before the drawbar stop 217 has been 30 pushed back, the flat surface 245 of the stop cam 221 will abut against the upper surface of the cam projection 219 and thus hold the shaft 223 against clockwise rotation to the switch closed position. If the operator should move the draw bar stop 217 to its locking position and fail to move the draw bar stop 218 to its locking position, an attempted operation of the circuit breaker will be successful. Clockwise rotation of the shaft 230 brings the curved surface 224 of the stop cam 222 against the inclined surface of the cam projection 220 and forces this cam projection rearwardly to its locking position. This assures locking of the hoisting mechanism in its elevated position when the circuit breaker is in its closed position.
- 45 To lower the circuit breaker it is necessary first to trip it. Thereafter, the release bar pull rods 215-216 are pulled forward to bring the draw bar stops 217-218 out of the slots 96 and free of the interlock bars 230. The circuit breaker may then be lowered by rotating the hoisting mechanism operating shaft 88 which, through the mechanism previously described, rotates the worm 15 to cause the nut 76 to travel downwardly and thus lower the circuit breaker supporting and hoisting frame. When the circuit breaker reaches 50 its fully lowered position the top surfaces of the draw bar stops are immediately below the bottom surfaces of the interlock bars 230. The draw bar stops may then be pushed back to a position beneath the interlock bars, as indicated in dotted lines in Figure 11, and thus lock the circuit breaker elevating mechanism against being raised. In this position the cam projections 219-220 again clear the stop cams 221-222 and thus permit operation of the circuit breaker operating shaft 223, as may be necessary for test purposes. It is to be noted that the draw bar stops 217-218 can not be moved to a position clearing the cams 221-222 while the hoisting mechanism is only partially lowered, since at that time the interlock bars 230 prevent rearward movement of the draw bar stops 217-218. Thus it is impossible to reclose the circuit breaker when the same has been only partially lowered.

If an attempt is made to lower the hoisting mechanism while the draw bar stops 217-218 are in their locking position, that is, within the slots 96 and resting on the interlock bar 230, the front of the hoisting mechanism will be held against lowering. The attempted lowering of the rear end of the hoisting mechanism will cause the two angle members 107 to bind on the upright guides 105 and prevent lowering of the hoisting mechanism. A similar binding action 10 takes place if an attempt is made to raise the hoisting mechanism when the draw bar stops engagement of the lower face of the interlock bars 230 to lock the hoisting mechanism against elevation. 15

When the circuit breaker has been lowered and the draw bar stops 217-218 pushed back, it is possible to operate the circuit breaker. If the circuit breaker is operated to its switch closed position the stop cams 221-222 prevent retraction of the draw bar stops and thus prevent elevating of the circuit breaker. The circuit breaker can be elevated only when it is in its switch open position. 20

When the circuit breaker supporting mechanism has been lowered to the disconnecting position, the locking lug 97 on the hoisting arm 93 is opposite a lower clip angle 244 that is welded or otherwise secured to the outer flange of one of the channel members 231. This permits padlocking of 30 the circuit breaker in its disconnecting position. An upper clip angle 245, which is also welded or otherwise suitably secured to the outer flange of the upright structural member 231, permits padlocking of the hoisting mechanism in its elevated 35 position.

To completely remove the breaker element from the elevator element and frame, the breaker is lowered to the platform of a truck that may be inserted beneath the breaker and which then 40 takes the weight of the breaker element. The elevator element can be lowered further until the breakerelement is completely disengaged from the three points of support. The breaker can then be rolled forward and away from the structure. 45

From the above description it is apparent that we have invented an improved switching station comprising a compact structure having a high factor of safety since it is impossible to obtain an 50 incorrect operation of the kind that might be destructive. The circuit breaker is supported in its hoisting frame on a three-point support, thereby assuring a firm support for the breaker even if one of the point support is slightly above 55 or below the other two points. The circuit breaker is held against vertical upward movement in the elevator frame solely by its own weight whereby it may be inserted in place by simply lowering the elevator frame, moving the 60 circuit breaker between the arms of the frame, and then raising the frame until the arms engage the breaker. It may be removed from the frame in an equally simple manner. When the breaker is in its fully elevated position the hoisting frame 65 is held against downward movement by the draw bar stops 217-218 which are within the slots 96 and rest on the interlock bars 230. The circuit breaker is held against upward movement, under the explosive action that takes place during 70 violent circuit breaker operation, by the stops 246-246. Therefore the hoisting frame is practically freed from stress incident to the tripping of the circuit breaker.

While we have herein shown and described a 75

preferred embodiment of our invention, it is to be understood that the invention is not limited to the precise construction herein shown, the same being merely illustrative of the principles of the invention. What we consider new and desire to secure by Letters Patent is:—

1. Electric switching apparatus comprising a stationary structure, a main switch unit mounted to have vertical movement therein, said structure and unit having cooperating disconnecting switch contacts separable by downward movement of the unit, a switch operating member forming a part of the main switch unit, means carried by the switching unit and movable into engagement with the stationary structure for locking the switching unit in its uppermost position to said stationary structure, means carried at the ends of said operating member for locking the member against switch closing movement whenever the first mentioned locking means is in its released position, and means for preventing operation of said switch unit locking means when said unit is in intermediate positions.

2. Electric switching apparatus comprising a stationary structure, a main switch unit, a frame supporting said unit and mounted to have vertical movement in said structure, said structure and said unit having cooperating disconnecting switch contacts separable by a downward movement of the unit, means carried by the unit and movable into engagement with said frame and stationary structure for locking the unit against downward movement and for rigidly securing said unit against upward movement with respect to said frame, means carried by said structure for preventing engagement of said locking means except when said unit is in fully raised or fully lowered position, and means carried by said unit for preventing release of the locking means while the switching unit is in its switch closed position.

3. Electric switching apparatus comprising a stationary structure having disconnecting switch contacts, a switch unit having cooperating disconnecting switch contacts adapted when the switch unit is raised, to engage the first mentioned disconnecting contacts, a hoisting mechanism for raising the switch unit, a pair of locking members for preventing vertical movement of the switching unit, and means for preventing closing operation of the switch unit when both locking members are in their released position and for moving one of the locking members to its locking position responsive to an attempted closure of the switch unit when the other locking member is in its locking position.

4. Electric switching apparatus comprising a stationary structure having disconnecting switch contacts, a switch unit having cooperating disconnecting switch contacts engageable with said first disconnect contacts when said unit is raised, a hoisting mechanism supporting said unit for raising and lowering movement, abutment means on said structure for limiting the elevated position of said switch unit, and means responsive to a closure of the switch in its elevated position for preventing movement of said switch relative to said frame and movement of said frame relative to said stationary structure, said last named means being operable only when said switch unit is in fully raised or fully lowered position.

5. In combination, a stationary structure, a hoisting frame vertically movable in the structure, a circuit breaker supported by said frame and separable therefrom as a complete unit, and

means carried by the circuit breaker for simultaneously locking the circuit breaker to the hoisting mechanism and the hoisting mechanism to the stationary structure.

6. In combination, a stationary structure, a hoisting frame vertically movable in the structure, a circuit breaker supported by said frame and separable therefrom as a complete unit, means carried by the circuit breaker for simultaneously locking the same to the hoisting mechanism and locking the hoisting mechanism to the stationary structure, and means controlled by the locking means for controlling the operation of the breaker.

7. Electric switching apparatus comprising a stationary structure, a switch unit adapted to be raised and lowered therein, said stationary structure and said switch unit having cooperating disconnecting switch contacts adapted to engage when the unit is in its raised position, a hoisting mechanism supporting the switch unit, said unit resting upon the hoisting mechanism and depending therefrom and held against upward movement with respect to the mechanism solely by its own weight whereby the hoisting mechanism may be freed of the switch unit by a relative vertical movement, abutment means carried by the stationary structure and holding the switching unit against upward movement from its normal elevated position under the reactions incident to a violent circuit interruption, and means for simultaneously locking the switch unit and hoisting mechanism against downward movement from their uppermost position and resisting the downward reaction incident to a violent circuit interruption, said last-named means preventing closure of switch unit in said uppermost position except when said locking means is in locking position.

8. In combination, a circuit breaker including a head and a tank depending therefrom, supporting trunnions on the opposite sides of the head adjacent the front thereof, additional supporting means at the rear of the head, vertically movable supporting means for the breaker comprising a frame open at the front for receiving the breaker, said frame having a pair of parallel side arms each of which has a trunnion receiving groove cooperating with the trunnions on the breaker head, and means at the rear of the frame cooperating with the supporting means at the rear of the circuit breaker head.

9. In combination, a circuit breaker including a head, line conductors extending therethrough, and a tank depending from the head, said head having three supporting projections extending therefrom, and an elevator mechanism for the breaker, said elevator mechanism including a pair of arms adapted to embrace the breaker and engage two of the supporting projections, and a cross arm between the pair of arms, said cross arm engaging the third projection.

10. Electric switching apparatus comprising a stationary structure having disconnecting switch contacts, a switch unit having cooperating disconnecting switch contacts adapted when the switch unit is raised, to engage the first mentioned disconnecting contacts, a hoisting frame supporting the switch unit, means at the rear of the frame for supporting and raising it, means adjacent the front of the frame for locking it to the stationary structure, cooperating guides on the stationary structure and on the hoisting frame, and means for causing a binding action

at the guides if an attempt is made to move the hoisting frame vertically when the front end thereof is locked.

11. Electric switching apparatus comprising a stationary structure, a hoisting frame mounted in said structure, vertically movable means supporting the rear of the hoisting frame, means for locking the front of the frame to the structure, and means at the rear end of the frame for causing a binding between the hoisting frame and the stationary structure if an attempt is made to move the rear of the hoisting frame vertically while the front thereof is locked against movement.
15. 12. In a switch gear cubicle having vertical side channels therein, a switch unit adapted to be vertically raised and lowered within said cubicle, a hoisting mechanism therefor having roller means engaging in said channel and having means for supporting said switch unit thereon, slideable latch means carried by said unit and adapted to lock said unit to said mechanism, and means in said cubicle preventing actuation of said latch means in positions intermediate the upper and lower positions of said hoisting mechanism.

13. In a switch gear cubicle, a hoisting mechanism having guided vertical movement therein, a switch unit adapted to be supported in said hoisting mechanism, means carried by said unit for simultaneously locking said unit to said mechanism and said mechanism to said cubicle when in upper raised position, and means for causing a binding action on said mechanism with respect to said frame upon attempted vertical movement of said mechanism when said locking means is engaged.

14. Electrical switching apparatus including a switch unit, hoisting mechanism supporting said unit, means for preventing movement of said hoisting mechanism when said unit is in operative position, said means including a pair of latching members, and means responsive to operation of said unit when one of said members is in latching position for simultaneously moving the other of said members into latching position.

15. Electrical switching apparatus comprising a stationary cubicle structure having opposed guide channels formed in the sides thereof, hoisting mechanism in said cubicle forming a three-point bearing support for a switch unit, said mechanism comprising a supporting frame having a pair of laterally offset guide rollers at each side thereof engaging spaced guide surfaces on said channels to prevent cocking of said mechanism in one direction in said channels, means within said cubicle for raising and lowering said hoisting mechanism, and means on the switch engageable with the frame and the stationary structure for locking the switch to the frame and the frame to the cubicle structure in the elevated position of the frame and switch.

16. In electrical switching apparatus of the class described, a circuit breaker comprising a head portion and a depending tank portion, said head portion having three supporting projections, hoisting mechanism for said breaker having means engageable by said projections, a pair of slideable latching members carried by the head of said breaker, interlocking means formed in said hoisting mechanism, and an operating shaft for said breaker, said latching members preventing rotation of said shaft toward operating position until said latching members are moved into engagement with said interlocking means.

17. Electrical switching apparatus comprising a circuit breaker having a head portion and a depending tank portion, a pair of trunnions extending from opposite sides of said head portion, a supporting member secured to the rear of said head portion, a hoisting mechanism mounted for vertical movement and having an open end portion, parallel side members having trunnion receiving portions, a cross arm between said side members opposite the open end of said mechanism and having supporting means for receiving the supporting member on said head portion, said breaker being supported on said hoisting mechanism, and means for locking said breaker with respect to said hoisting mechanism only in fully raised or fully lowered position of said mechanism.

18. Electrical switching apparatus comprising a circuit breaker having a head portion and a depending tank portion, a pair of trunnions extending on opposite sides of said head portion, a supporting member secured to the rear of said head portion, a hoisting mechanism mounted for vertical movement and having an open end portion, parallel side members having trunnion receiving portions adjacent said open end portion, a cross arm between said side members at the opposite end thereof and having supporting means for receiving the supporting member, said breaker being supported by said trunnions and supporting member on said hoisting mechanism, means for locking said breaker with respect to said hoisting mechanism only in fully raised or fully lowered position of said mechanism, and means for preventing operation of said breaker into switch connecting position until said breaker is locked to said hoisting mechanism.

19. In electrical switching apparatus of the class described, a stationary cubicle structure, a hoisting frame, means in said structure providing a guideway for vertical movement of said hoisting frame, supporting means formed in said hoisting frame, a switch unit, means carried by said unit and engageable with said supporting means to support said unit in position within said frame, said unit being vertically separable from said frame, and latching means carried by said unit and adapted to lock said unit to said frame only in uppermost and lowermost positions of said frame.

20. In electrical switching apparatus of the class described, a stationary cubicle structure, a hoisting frame, means in said structure providing a guideway for vertical movement of said hoisting frame, supporting means formed in said hoisting frame, a switch unit, means carried by said unit and engageable with said supporting means to support said unit in position within said frame, said unit being vertically separable from said frame, and latching means carried by said unit and adapted to lock said unit to said frame only in uppermost and lowermost positions of said frame, said latching means simultaneously engaging said stationary structure for preventing movement of said frame.

21. In combination, in switchgear of the class described having depending disconnect contacts mounted in the upper portion thereof, a hoisting frame mounted for vertical movement beneath said contacts, a switch unit detachably supported on said frame and having line terminal contacts adapted to engage said disconnect contacts, a rotatable operating shaft for said unit, latching means carried by said unit and adapted to lock said unit to said hoisting frame in uppermost position of said frame, said

latching means having means for preventing rotation of said shaft into operating position when said unit is not locked to said frame.

22. In combination, a stationary frame structure, a hoisting mechanism therein, a circuit breaker movable into and supported on said hoisting mechanism, stop means on said frame limiting upward movement of said breaker, releasable means carried by said breaker and operable only when said breaker is in uppermost position to lock said breaker against downward movement with respect to said frame and simultaneously to lock said hoisting mechanism to said frame, and means for holding said locking means in locking position when said breaker is in switch closed position.

23. Electrical switching apparatus comprising a stationary cubicle structure having opposed guide channels formed in the opposite sides thereof, a hoisting frame mounted only for vertical movement in said cubicle comprising a pair of opposed side portions having guide means engaging the guide surfaces of said channels to prevent cocking of said frame in said structure, 20 a switch unit freely supported on the frame for

vertical movement with said frame, means carried by said unit for locking said unit to said frame, means on said cubicle structure simultaneously engaged by said locking means when said frame is in elevated position whereby said frame is locked to said structure, and means on said cubicle structure for preventing operation of said locking means when said unit is in intermediate vertical positions.

24. A hoisting frame for electrical switching apparatus of the class described, comprising a pair of spaced supporting members, a cross bar therebetween, a pair of parallel arms extending normal to said members and cross bar, strut members extending between the extending ends 15 of said arms and said members, means at the extending ends of said arms and intermediate the ends of said cross bar for supporting a switch unit thereon for free vertical movement with respect to said frame and against lateral move- 20 ment with respect thereto.
